UNITED STATES PATENT OFFICE.

GEORGE E. HAYES, OF BUFFALO, NEW YORK.

APPARATUS FOR VULCANIZING RUBBER.

Specification of Letters Patent No. 28,668, dated June 12, 1860.

To all whom it may concern:

Be it known that I, GEORGE E. HAYES, of the city of Buffalo and State of New York, have invented certain new and useful Improvements in Flasks and Clamps for Vulcanizing Rubber Compound for Bases of Artificial Teeth; and I do hereby declare that the following is a full and exact description thereof, reference being had to the accompanying drawings, and the letters of reference marked thereon, making a part of this specification, in which—

Figure I, is a perspective of the packing clamp and flask as used in combination. Fig. II, is a section of same. Fig. III, is an elevation of two flasks and clamp as put together for vulcanizing. Fig. IV, is a perspective of the top plate of the flask.

Fig. V, is a perspective of the main body or middle portion of the flask. Fig. VI, is a perspective of the lower plate of the flask.

Letters of like name and kind refer to like parts in each of the figures.

A, Figs. I and II, represents the bottom piece of the packing clamp made of cast iron having a central opening, b, and circular groove, c, and upward projection or back d.

E represents a rod of spring steel which screws into the bottom piece A, and is also braced or supported by the back d. It rises perpendicularly about three inches in the packing clamp and about six inches (more or less) in the vulcanizing clamp and then bends over, so as to overhang the bottom piece as shown at E'. A set screw F, passes through this overhanging part, by which any required amount of compression can be applied to the flask.

The flask is made in three parts. The upper part is shown at G (Figs. I, II, III, and IV). It has a circular emboss as shown at g' and countersinks to receive the end of the set screw as shown at g². It also has small projecting nibs as shown at g³ which nibs fit inside of the middle piece, H, and hold it in place when the two parts are put together. It also has a semi-circular recess as shown at I, for the purpose of affording room for the spring rod (E) within the outer circle of the flask. As a modification of this recess a simple hole may be made through the flask but in practice I prefer the recess as more convenient and efficient.

H, represents the main body or central part of the flask. This is made suffi-

ciently deep to hold the plaster mold in connection with the bottom piece. It has projecting nibs h' which fit into corresponding recesses, j' in the bottom piece when they are put together. It also has a semicircular recess, I, for the reception of the spring rod E.

J, represents the bottom part of the flask. Its sides or rim (J²) rise about half an inch so as to form a sort of cup or basin. It also has a circular recess or depression as shown at j', Fig. III, which depression corresponds to the circular emboss on the upper plate. It also has a semi-circular recess I, for the reception of the back (d) of the clamp. These recesses correspond in each part of the flask, so that when the three parts are put together and the flask put into the clamp, the back d, and spring rod E will occupy this recess, so that a vulcanizer of no larger diameter will be required on account of the clamp than is required for the flask alone, the clamp being contained within the outer circle of the flask, and the flask being so constructed as to occupy the least possible space.

The improvements in the flask and clamp herein described enable me to bring my whole apparatus to the smallest possible dimensions, and hence I can vulcanize the rubber compound with about half the volumes of steam hitherto used, and hence cheapen the process and render it more safe. The emboss, g', in combination with the depression, j', serve to prevent the flasks from slipping sidewise when put into the clamp.

The clamp represented in Fig. III varies slightly from the one shown in Figs. I and II. The bottom piece has a depression to admit the emboss of the upper plate as shown at a'. The spring rod is also made longer so as to receive three flasks for vulcanizing at the same time, and the bent portion of it a little shorter so as to bring the point of the set screw on or over the center of the flask as shown in Fig. III.

K, represents a cast iron blank which is used to fill up the space between the flasks and set screw. When but two flasks are put into the clamp it sets in the circular depression made in the bottom piece of the flask as shown in Fig. III, and has a countersink at the top for the point of the set screw. In case there should be but one flask put into the clamp, then a longer blank occupying the space of two flasks should be used in like

manner. When three flasks are put into the clamp they will fill up the entire space so that the set screw will strike upon the upper flask, in which case no blank need be used.

5 Operation: The rubber compound is put into the packing flask in the usual manner, and the flask is then put into the packing clamp as represented in Figs. I and II. The set screw is then turned down so as to strain 10 the spring rod, E, and press heavily upon the flask. As the rubber compound is gradually softened by warming the flask, it will yield to the pressure, and the reaction of the spring rod will follow up the yielding na- 15 ture of the softened compound, and thus keep a continual and uniform pressure upon the compound until it is brought within its required dimensions in the flask. The position of this flask may be changed in the 20 clamp so as to bring either one of the countersinks, (g²) under the set screw, and thereby vary the point of greatest pressure, as may be required. After passing through this process in the packing clamp, the flask 25 is put into the vulcanizing clamp Fig. III in a reversed position. One, two, or three flasks may be put into this clamp, as before

described, the emboss of one fitting into the depression of the other, and the whole put into the vulcanizer with the set screw downward, and the rubber compound in each flask will be vulcanized at the same time.

The vulcanizer can be made very compact and strong, with a cylinder just large enough to receive the flasks, and so that a half pint 30 of water will be sufficient to generate steam enough for the purpose.

What I claim as my improvement in vul- 35 canizing apparatus, and as my invention, is—

1. A spring clamp, constructed and operating for the purpose, and substantially as herein described.
2. Constructing the flask with a recess I, for the purposes, and substantially as set 40 forth.
3. The circular emboss (g') in combination with the corresponding depression j³, for the purposes substantially as described.

GEO. E. HAYES.
